TIRE COVER

George W. Walker, Bloomfield Hills, Mich., assignor to Ford Motor Company, Dearborn, Mich., a corporation of Delaware

Filed Jan. 12, 1959, Ser. No. 54,148

Term of patent 7 years

(CL. D14—30)

Fig. 1 is a front elevational view of a tire cover according to my new design;

Fig. 2 is a sectional view taken on the plane indicated by the line 2—2 of Fig. 1; and

Fig. 3 is a perspective view of the tire cover.

The tire cover being substantially plain when viewed from the back, the rear elevational view thereof is not shown.

I claim:

The ornamental design for a tire cover, substantially as shown and described.
